ATTORNEY.

UNITED STATES PATENT OFFICE.

FRITZ KOERBITZ, OF SAN FRANCISCO, CALIFORNIA.

SOUND-REPRODUCER MOUNTING.

1,387,410.

Specification of Letters Patent.

Patented Aug. 9, 1921.

Application filed May 4, 1920. Serial No. 378,894.

To all whom it may concern:

Be it known that I, FRITZ KOERBITZ, a citizen of the United States of America, residing at San Francisco, in the county of 5 San Francisco and State of California, have invented new and useful Improvements in Sound-Reproducer Mountings, of which the following is a specification.

My invention relates to an improvement 10 in mountings for sound recording and reproducing members used in connection with phonographs, and has particular reference to a mounting on which is placed an improved sound reproducing member as a substitute for the ordinary stylus or needle.

An important object of this invention is 20 to provide a sound reproducing member of a disk shape, which will answer the same purposes as a stylus or needle as used on a phonograph and yet have an additional advantage of longer duration in wear.

Much annoyance has been experienced in 25 the use of sound reproducing members because of the rapid wearing of the phonograph needle or stylus and the consequent frequent substitution of a new needle for the old one. This difficulty my invention overcomes by the use of the disk shaped member and in addition to the features of 30 preventing a rapid wearing of a sound reproducer and also the deterioration of a phonograph record, has the advantage of giving forth a better sound by providing means whereby the periphery of the disk 35 shaped sound reproducing member contacts with the phonograph record.

Another object of the invention is the provision of my improved mounting for the disk shaped member, which holds the disk 40 shaped member in a fixed vertical position and provides means for a quick adjustment of a new disk shaped sound reproducing member when the same is desired.

A still further object of the invention is 45 to provide a sound reproducing member with the improved form of mounting of the above mentioned character, which is simple in construction, inexpensive to manufacture, strong, durable, and reliable in operation.

50 Other objects and advantages of my invention will be apparent during the course of the following description:

In the accompanying drawings forming a 55 part of this specification and in which like numerals are employed to designate like parts throughout the same, Figure 1, is a

front elevation of the apparatus embodying my invention. Fig. 2, is a side elevation of my device with a conventional form of retaining means for the shank shown partly 60 in section. Fig. 3, is a front elevation showing the spindle released from one of the arms of the bracket and pivoted to the other arm. Fig. 4, is an enlarged detail vertical section of the disk shaped member mounted 65 on the spindle and showing means for retaining the disk member in a vertical position, and Fig. 5, is a side elevation showing the slotted arm of the bracket and means for holding the spindle pivoted. 70

In the accompanying drawings wherein for the purpose of illustration is shown a preferred embodiment of my invention the numeral 6 designates a shank suitably attached to the body portion of a bracket 7, 75 preferably threaded thereon, which bracket is held fixed on the shank 6 by means of a nut 8. It will be noted that the upper end of the shank can be suitably attached to a connecting lever, which attachment forms no 80 part of my invention, and that the bracket 7 terminates in arms 9 and 10 which are slotted at 11 and 12 respectively, and which slotted portions receive the respective ends 13 and 14 of a spindle 15. The spindle 15 85 is pivoted to the arm 10 by a fastening pin 16 at one end thereof while it is detachably fixed on the arm 9 by a suitable fastening hook 17.

As more clearly shown in Fig. 4 the 90 spindle 15 has mounted thereon adjacent the end 14 an integral stop 18 while it is screw threaded adjacent the other end 13 as shown at 19 to receive an adjustable stop 20. Before the stop 20 is adjusted on the spindle 15 95 my improved sound reproducing member 21 of a disk shape is placed upon the spindle 15 and the adjustable stop 20 when placed on the spindle acts in conjunction with the integral stop 18 and holds the sound reproducing member in a vertical position as its circular edge rests in a groove of a phonograph record as it travels over the record and reproduces the sound waves. 100

The operation in adjusting the disk 105 shaped member in position for use in connection with a phonograph record is as follows:—The shank 6 is attached to a lever arm of a phonograph as referred to before and when it is desired to place a new disk 110 sound reproducing member on the pivoted spindle 15, the free end 13 of the spindle

is released from the fastening hook 17 and the adjustable nut 20 is unscrewed from the threaded portion 19 of the spindle 15. After this step the disk shaped member 21 is placed on the spindle 15 and rests against the rounded edge of the integral stop 18. The adjustable stop 20 is then screwed onto the spindle 15 until it takes a position almost touching the disk 21. After the disk 10 is in position the free end 13 of the spindle 15 is fastened to arm 9 and is there held in position. It will thus be observed as mentioned before, that the fixed integral stop 18 and the adjustable stop 20 tend to hold 15 the disk 21 in a vertical position and will prevent a lateral movement of the disk member 21 as it travels over the record of a phonograph in the act of reproducing sound.

The construction as set forth in Fig. 2, 20 showing a lever arm 22, a link 23, a set screw 24 and a diaphragm 25 illustrate the manner in which my improved mounting may be connected with a phonograph and it is to be understood that no claims of novelty 25 are made for these particular features.

It is hereby understood that the form of invention herewith shown and described is to be taken as a preferred embodiment of the same, and that various changes in the 30 shape, size, and arrangement of parts may be resorted to without departing from the

spirit of the invention or the scope of the subjoined claims.

Having thus described my invention I claim:—

1. A stylus mounting comprising a shank, a bracket secured to said shank and terminating in slotted arms, a spindle pivoted at one end to one arm of said bracket, and detachably fastened to the other arm of said bracket, a disk shaped sound reproducing member mounted on said spindle, and stops on said spindle to retain said sound reproducing member in a vertical position, one of said stops being integral with said spindle, 40 and the other of said stops being adjustable on said spindle.

2. A stylus mounting comprising a shank, a bracket terminating in slotted arms and secured to said shank, a spindle threaded 50 partly throughout its length and pivoted to one arm of said bracket, a disk shaped sound reproducing member mounted on said spindle, stops on said spindle to retain said disk shaped sound reproducing member in 55 a vertical position with relation to a phonograph record, and means for fastening the free end of the spindle to the other arm of said bracket.

In testimony whereof I affix my signature. 60

FRITZ KOERBITZ.
